EXTRACTOR TOOL

Charles Ferguson, Edinburgh 9, Scotland

Application July 15, 1942, Serial No. 451,084
In Great Britain March 17, 1942

2 Claims. (Cl. 254—30)

This invention relates to a new or improved tool for extracting the base end of an article from a base or foundation in which it is fixed, the improved tool being primarily designed for extracting the stumps of metal or other posts, standards or vertical bars of demolished fences or railings from the coping of the wall or other foundation in which the stumps remain fixed after the fence or railing has been demolished. Although the improved extracting tool has been primarily designed for extracting fence stumps, it will be apparent from the appended description and drawing that the improved tool can be utilised for extracting bolts or other articles from the base or foundation in which they are secured.

According to the present invention the improved extracting tool comprises a clamping member having means for gripping the article to be removed at a point above the base or foundation in which the article is fixed, and one or more manually operable elements carried by the clamping member and adapted to bear against the said base or foundation or against a bolster or seating block which may be interposed between the clamping member and the base or foundation in which the article is fixed, the said elements, when operated, being adapted to raise the clamping member by the reaction of the said elements against the base or foundation on which they directly or indirectly bear.

The clamping member is preferably a metal or other block centrally apertured to fit over the article to be removed and provided with one or more adjustable clamping jaws for gripping the article, and with one or more manually operable cams or eccentrics fulcrumed on the clamping member and adapted to bear with the cam surfaces or peripheries of the eccentrics upon the base or foundation or upon the interposed bolster. The manually operable cam or eccentric or each of such cams or eccentrics conveniently has a handle attached thereto for rotating the cam or eccentric with its cam surface in contact with the base or foundation or in contact with the interposed bolster in order to raise the clamping member and extract the base end of the article therefrom. The clamping jaws preferably comprise a pair of eccentrically mounted toothed or serrated cams or discs fulcrumed in the clamping block at opposite sides of the aperture therein, each serrated eccentric jaw being attached to one end of a handle whereby the jaw may be turned in the clamping member to grip the article. The eccentric mounting of the clamping jaws is such that the pull on the ar-

title during the process of extraction tends to rotate the clamping jaws in the direction in which the grip of the jaws on the article is increased.

In order to restrict or limit fracture of the base or foundation during the extraction process, particularly when extracting fence stumps from the coping of a wall or other foundation in which the stumps are fixed, it is preferred to provide a bolster or seating block between the clamping member and the coping of the wall or other foundation, this bolster being preferably a metal block centrally apertured to fit over the fence post or like article, and the lower face of the bolster being provided with a projecting rim surrounding the lower end of the central aperture through the bolster and this rim being preferably sharpened or knife-edged in order that this projecting rim will force itself into the coping of the wall or other foundation under the reaction pressure which occurs during the extraction of the fence post or like article. The top surface of the bolster is preferably flat and forms a support for the clamping member which may also be in the form of a metal block having a central aperture through it to enable the clamping member to be fitted over the fence post until the clamping member rests on the bolster.

The accompanying drawing illustrates the preferred manner of carrying out the invention, Fig. 1 being a side view, Fig. 2 an end view, and Fig. 3 a plan view of the extracting tool in its preferred form. Fig. 4 is a vertical sectional view on the line 4—4 of Fig. 3, showing a fence stump in position.

The tool illustrated comprises a clamping block 5 having a vertical central aperture 6 to enable it to be fitted over the fence post 7 or other article having its base end 8 fixed in the coping of a wall or other foundation 9. The block 5 is rectangular and has slots 10 in two opposite sides to receive toothed or serrated clamping jaws 11 which are eccentrically pivoted on transverse pivot pins 12 secured in the block 5. Attached to and projecting from each serrated jaw 11 is a handle 13 and it will be observed that the handles 13 are in alignment and extend in opposite directions when the jaws 11 are clear of the fence post. By turning the handles 13 about the centres of the pivot pins 12, the jaws 11 may be caused to grip the fence post. For raising the clamping block 5 a pair of manually-operable cams or eccentrics 14 is provided, these cams or eccentrics being pivotally mounted on the outside of the block 5 at the two sides not occupied by the jaws 11. Each eccentric 14 is mounted on a

pin 15, the two pins 15 being coaxially arranged in the block 5. Each eccentric 14 is also attached to one end of an operating handle 16 and as shown on the drawing, the arrangement may be such that each operating handle 16 is horizontal (or nearly so) when the vertical distance between the fulcrum pin 15 and the lower periphery of the eccentric 14 attains its minimum and maximum respectively, so that, by swinging the handle 16 through 180 degrees or thereabouts, the eccentric 14 will raise the block 5 above the bolster 17 by an amount equal to the eccentric throw. The handles 16 preferably normally extend in opposite directions as shown, so that by turning one handle in the clockwise direction and simultaneously turning the other handle in the anti-clockwise direction, both eccentrics 14 will be rotated in the required direction to raise the block 5 with the fence post 7 clamped thereto.

It will be apparent that the block 5 and the peripheries of the eccentrics 14 may bear directly upon the top of the foundation 9, but in order to restrict fracture of the foundation 9, it is preferred to interpose a bolster 17 which has a central aperture 18. A centering washer 19 is fitted in the upper part of the aperture 18, the washer 19 being apertured to fit over the fence post 7. Recessed into the lower part of the bolster 17 is a hardened ring 20 having a circular projecting knife-edge 21 which is forced into the top of the foundation 9 by the downward pressure on the bolster 17 when the handles 16 are operated to raise the block 5.

In order to enable the positions of the handles 16 with respect to the eccentrics 14 to be adjusted to suit varying conditions of working, particularly in confined places where it is not possible for the handles to extend out in opposite directions in a horizontal position, the handles 16 are detachably and adjustably secured to the ec-

centrics 14. As shown, each eccentric has a central projecting pin 22 adapted to fit a corresponding hole in the flattened end portion 16a of the handle 16, which is provided with a laterally projecting stud 23 which can be entered in any one of a number of holes 24 in the eccentric 14. When the hole in the end portion of the handle 16 has been engaged with the central pin 22 and the stud 23 has been engaged in one of the holes 24, the handle 16 can be secured in that position by a screw 25 driven into one of a series of screw holes 26 in the eccentric 15.

I claim:

1. An extracting tool comprising a block having a vertical central aperture therethrough and transverse slots in two opposite sides, a pair of serrated clamping jaws eccentrically pivoted in said slots, a handle attached to each of said jaws, a pair of cam discs eccentrically pivoted on pivot pins on the outside of said block at the two sides not occupied by said jaws, a handle attached to each of said cam discs for rotating it about its pivot, means detachably securing each cam disc to its handle, and means for varying the angular setting of each cam disc with respect to its handle.

2. An extracting tool comprising a block having a vertical central aperture therethrough and transverse slots in opposite sides, a pair of serrated clamping jaws eccentrically pivoted in said slots, a handle attached to each of said jaws, a pair of cam discs pivoted on aligned pivot pins on the outside of said block at the two sides not occupied by said jaws, said pins having their axes parallel to the pivotal axes of said jaws, a handle associated with each of said cam discs for rotating it about its pivot, means detachably securing each cam disc to its associated handle, and means for varying the angular setting of each cam disc with respect to its handle.

CHARLES FERGUSON.
